US0D1105268S

(12) **United States Design Patent** (10) **Patent No.:** **US D1,105,268 S**
(45) **Date of Patent:** **** Dec. 9, 2025**

(54) **SCOOTER**

(71) Applicant: **ZHEJIANG TAOTAO VEHICLES CO., LTD.**, Lishui (CN)

(72) Inventors: **Jianbing Wu**, Xianning (CN); **Daqing He**, Xianning (CN); **Guofu Zou**, Xianning (CN); **Kai Xie**, Xianning (CN); **Meijun Li**, Xianning (CN); **Xubin Ding**, Xianning (CN); **Zhihui Gan**, Xianning (CN); **Pengju Li**, Xianning (CN)

(73) Assignee: **ZHEJIANG TAOTAO VEHICLES CO., LTD.**, Lishui (CN)

(**) Term: **15 Years**

(21) Appl. No.: **29/928,087**

(22) Filed: **Feb. 8, 2024**

(30) **Foreign Application Priority Data**

Dec. 13, 2023 (CN) 202330821253.5

(51) LOC (15) Cl. **12-12**

(52) U.S. Cl.

USPC **D12/131**
